UNITED STATES PATENT OFFICE

STANLEY A. JACQUES, OF CHICAGO, ILLINOIS, ASSIGNOR TO INTERNATIONAL COMBUSTION ENGINEERING CORPORATION, OF NEW YORK, N. Y., A CORPORATION OF DELAWARE

BOILER INSTALLATION

Application filed January 25, 1929. Serial No. 334,893.

This invention relates to improvements in boiler installations and particularly to installations embodying horizontal tube box header boilers associated with boiler-furnaces, i. e., furnaces having evaporating surfaces in the form of water walls arranged to define combustion space thereof.

In boiler installations the present demands are for the development of high capacities with the installations operated at very high rates of firing. In attempts to meet the demands steam evaporating walls have been provided for the combustion chambers of standard boilers so as to increase their capacity. This, however, in many instances, results in operating difficulties because standard boilers are not always adapted in their design to take care of conditions produced by steam evaporating walls. I have found that operating difficulties are particularly present in such installations when employing standard horizontal tube, box header boilers. Among difficulties encountered are the tendency to cause reverse flow through certain of the boiler tubes of the standard boiler, the lack of proper water supply to the steam evaporating tubes, and moisture in the steam.

The primary object of my invention is to provide a horizontal tube, box header boiler which is adapted to be embodied in high capacity installations of the character set forth and in which the above mentioned difficulties are overcome.

Another object of my invention is to provide a boiler of the horizontal tube, box-header type of such construction as to be particularly adapted to the peculiarities of steam evaporating surfaces of the furnace.

Stated in another way, I propose to coordinate the requirements of the boiler and steam evaporating surfaces of the furnace by adapting the design of each to the peculiarities of the other.

Other objects reside in certain features of construction appearing hereinafter.

How the foregoing, together with such other objects and advantages as may herein-after appear, or are incident to my invention,

are realized is illustrated in preferred form in the accompanying drawings, wherein:

Fig. 1 is a sectional elevation of a boiler installation constructed in accordance with my invention.

Fig. 2 is in part a sectional view and in part an elevational view, the left hand half of the view being a section taken on the line 2—2 of Fig. 1 and looking in the direction of the arrows, and the right hand half being a front elevation looking in the same direction as the section.

Fig. 3 is a fragmentary plan section taken on the line 3—3 of Fig. 1.

Fig. 4 is a fragmentary plan section similar to Fig. 3, but illustrating a modification of the invention.

Fig. 5 is a vertical section through a side wall adapted to be employed with the modification shown in Fig. 4.

Fig. 6 is an enlarged fragmentary view illustrating a detail of my invention.

Referring now more particularly to Figs. 1 and 2, the installation comprises, in general, a boiler A, a furnace or combustion chamber B, located below the boiler, and burner means C for introducing pulverized fuel and air into the combustion chamber. The burner or burners may be of any suitable type for admitting pulverized fuel and air into the chamber in a manner to produce turbulence, and, as here shown, are of a type to produce a swirling flame.

The boiler A comprises a plurality of rows of substantially horizontal tubes in this instance arranged in two spaced groups *a* and *b*; a box header 6, hereinafter referred to as the lower box header, into which one end of tubes are connected; a box header 7, hereinafter referred to as the upper box header, into which the other ends of the tubes are connected; a cross drum 8; a plurality of rows of tubes *c* for connecting the upper portion of the upper box header 7 with the cross drum 8; a plurality of rows of connectors 9 leading from the drum to the header 6; and suitable baffling as indicated at 10 for causing the gases of combustion leaving the combustion chamber B to take a tortuous path over and among the tubes of the boiler A. A su-

perheater 11 may be located in the space 12 as shown.

The combustion chamber B in substantial portion is defined by steam evaporating surfaces 5 in the form of a plurality of rows of boiler tubes in the chamber, each serving to define combustion space. In the preferred arrangement shown the rear wall 13 of the combustion chamber is lined with a row of 10 upright tubes 14, and the side walls 15, 15 each are lined with a row of upright tubes 16. A row of spaced tubes 17 extends across the lower portion of the combustion chamber, the spacing being sufficiently wide to permit ash 15 particles to gravitate through the spaces between the tubes into an ash chamber 18 therebelow.

The tubes of the row 14 preferably bend outwardly at their lower end portions for 20 connection into headers or junction boxes 19. The tubes of the row 17 incline upwardly from the front to the rear of the combustion chamber and pass thru the rear wall 13 for connection into the junction boxes 19 and 25 at their other ends they are connected into the header 20.

The tubes of the rows 16 are connected at 30 their lower ends into headers 21 and at their upper ends into headers 22, the headers, in the form illustrated in Figs. 1 and 2, being located outside of the combustion chamber and the tubes being bent to pass through the side walls to the headers.

Water is led from the boiler A to the bottom screen 17 by means of a plurality of 35 downcomers 23, the water being taken from the lower portion of the lower box header 6. The downcomer tubes extend into the header 6 to a point somewhat above the bottom of the header, i.e., to a point above the normal level 40 of deposit in the header so as to avoid drawing the deposit into the screens. The tubes may be extended to such point by means of nipples 24 attached thereto.

45 A plurality of downcomers 25 lead water from the lower box header 6 to the lower headers 21 of the side wall screens. These downcomers extend into the header 6 in the manner just described in connection with the 50 downcomers 23.

The upper end portions of the tubes of the rear wall screen 14 are bent for connection into the upper box header 7, the connections being preferably arranged in a row below the 55 lowermost row of boiler tubes. The tubes of the screen 14, however, do not deliver into the lower portion of the header 7, for I have associated an extension pipe or long nipple 26 with each tube of the screen which serves, 60 in effect, to bring each tube into the inside of the header. The nipples are of a length to bring the open or discharge end thereof to a level well above the bottom of the header whereby delivery from the screen into the 65 header is at a level such that circulation

difficulties are prevented, as, for example, reversal of flow through the lower rows of tubes of the boiler.

The nipples or extension pipes 26 may be movably attached to their associated tubes, as 70 illustrated in Fig. 6 for example, so as to enable of their being moved or swung to one side to give access to the boiler tubes for cleaning, rolling, tube removal, or other purposes.

A plurality of upcomers 27 are provided 75 for the side wall screens, which upcomers lead from the upper side wall headers 22 into the upper box header 7. These upcomers also connect into the header 7 at points well above the bottom thereof for reasons just explained in connection with the rear wall screen.

In contradistinction to the usual construction of the upper box headers of boilers of 85 this type, which is to make the headers of a width just sufficient to accommodate the width of the boiler tube bank or banks, I propose to make the upper header 7 of a width sufficiently wider than the tube bank or groups as will give ample surface at the sides 90 of the tube bank for the connection of the upcomers 27 thereinto. This is clearly illustrated in Fig. 3 in which the extra width is indicated at 28.

It will be seen that all downtake connection for the various steam evaporating tubes 95 in the combustion chamber are taken from the lower portion of the lower box header of the boiler at a point above the level of deposit therein, and that the steam generated 100 in these tubes is led into the upper box header at a level such as to prevent the screen circulation from interfering with the boiler circulation.

All of the steam from the screens and from 105 the boiler A enter the upper box header 7 and from thence it goes to the cross drum 8 at low velocity through the plurality of rows of tubes c, it being preferable to employ at least three rows of such tubes to ensure low 110 velocity.

With all of the steam entering the drum in 115 this manner and because of the manner of delivering steam from the upright walls into the box header 7, low moisture content in the steam is assured.

By employing a plurality of rows of downtakes 9 from the drum 8 to the lower box header 6 ensures a good supply of water to the boiler and screens.

Referring now to Figs. 4 and 5, I have 120 illustrated therein a side wall screen 16a in which the upper header 22a is embedded in the side wall of the installation, and in which the risers or upcomer tubes 27a are also embedded in the wall.

By having the tubes of the rear wall screen 14 connected into the upper box header 7 in the manner set forth, support is afforded for 125 this end of the boiler A, and, therefore, the 130

supporting beam usually placed under the header may be dispensed with.

From the foregoing it will be seen that I have provided a novel boiler of the horizontal tube, box header type which peculiarly meets the requirements of such boilers when embodied in high capacity installation employing a large amount of steam evaporating or screen surface within the furnace.

10 I claim:—

1. The combination with a boiler having a plurality of substantially horizontal tubes and upper and lower box headers into which the tubes are connected, of a combustion chamber associated with the boiler, a plurality of rows of steam evaporating tubes in the chamber each serving to define combustion space, downcomer means leading to said rows of tubes, and upcomer means leading from said rows of tubes to the upper box header and delivering upwardly thereinto well above the bottom of said header.

2. The combination with a boiler having a plurality of substantially horizontal tubes and upper and lower box headers into which the tubes are connected, of a combustion chamber associated with the boiler, a plurality of rows of steam evaporating tubes in the chamber each serving to define combustion space, downcomer tubes for leading water from the lower box header to said rows of tubes, said tubes opening into said header above the normal level of deposit in the header, and upcomer tubes for said rows of tubes, certain of said upcomer tubes extending upwardly within the upper box header and terminating well above the bottom of the header, and the remaining upcomer tubes being connected into a wall of 40 said upper header at points well above the bottom of the header.

3. The combination with a boiler having a plurality of substantially horizontal tubes and upper and lower box headers into which the tubes are connected, of a combustion chamber associated with the boiler, a plurality of rows of steam evaporating tubes in the chamber each serving to define combustion space, downcomer means leading to 50 said rows of tubes, and upcomer means leading from said rows of tubes to the upper box header, said upper header being wider than required to accommodate the plurality of substantially horizontal tubes whereby 55 surface is provided for the accommodation of upcomer means from rows of said steam evaporating tubes.

4. The combination with a boiler having a plurality of rows of boiler tubes inclined somewhat from the horizontal and upper and lower box headers into which the tubes are connected, said upper box header being extended in width beyond the width necessary to accommodate said boiler tubes, of a combustion chamber associated with the boiler,

a row of upright steam evaporating tubes defining each side wall of the chamber, downcomer tubes leading from said lower header to said side walls and upcomer tubes leading from said side walls to said upper header, the connections being made into the extended portions of said header.

5. The combination with a boiler having a plurality of rows of boiler tubes inclined somewhat from the horizontal and upper and lower box headers into which the tubes are connected, said upper box header being extended in width beyond the width necessary to accommodate said boiler tubes, of a combustion chamber associated with the boiler, 70 a row of upright steam evaporating tubes defining each side wall of the chamber, downcomer tubes leading from said lower header to said side walls and upcomer tubes leading from said side walls to said upper header, the connections being made into the extended portions of said header and at points above the level of the lower rows of boiler tubes.

6. The combination with a boiler, having a plurality of rows of boiler tubes inclined somewhat from the horizontal and upper and lower box headers into which the tubes are connected, of a combustion chamber associated with the boiler, a plurality of rows of steam evaporating tubes in the chamber each serving to define combustion space, the tubes of one of said rows of steam evaporating tubes being connected into the upper box header, and upright tubes within said upper header connected to the tubes of the last mentioned row so as to constitute extensions therefor and of sufficient length to lead the delivery from the evaporating tubes into the header at a level well above the bottom thereof.

7. The combination with a boiler having a plurality of rows of boiler tubes inclined somewhat from the horizontal and upper and lower box headers into which the tubes are connected, of a combustion chamber associated with the boiler, a plurality of rows of steam evaporating tubes in the chamber each serving to define combustion space, the tubes of one of said rows of steam evaporating tubes being connected into the upper box header, and upright tubes within said upper header connected to the tubes of the last mentioned row so as to constitute extensions therefor adapted to lead the delivery from the evaporating tubes into the header at a level well above the bottom thereof, said extension tubes being movably attached to the evaporating tubes.

8. The combination with a boiler having a plurality of substantially horizontal tubes and upper and lower box headers into which the tubes are connected, said upper header being wider than required to accommodate the plurality of substantially horizontal tubes, of a combustion chamber associated

with the boiler, steam evaporating tubes in said chamber, downcomer means leading to said evaporating tubes, and upcomer means leading from the evaporating tubes to the upper box header including tubes connected into the widened portions of the upper header, and tubes extending upwardly within the upper header and terminating well above the bottom thereof.

upper header and extending to points above the level of the lower rows of boiler tubes. In testimony whereof I have hereunto signed my name.

STANLEY A. JACQUES. 70

- 10 9. The combination with a boiler having a plurality of rows of boiler tubes inclined somewhat from the horizontal and upper and lower box headers into which the tubes are connected, said upper box header being ex-
15 tended in width beyond the width necessary to accommodate said boiler tubes, of a combustion chamber associated with the boiler, steam evaporating tubes in said chamber, downcomer tubes leading from said lower header to said evaporating tubes, said downcomer tubes extending upwardly within the lower header and terminating above the normal level of deposit therein, and upcomer tubes leading from said evaporating tubes to
20 said upper header, the connections being made into the extended portions of said header.

10. The combination with a boiler having a plurality of rows of boiler tubes inclined somewhat from the horizontal and upper and lower box headers into which the tubes are connected said upper box header being extended in width beyond the width necessary to accommodate said boiler tubes, of a combustion chamber associated with the boiler, steam evaporating tubes in said chamber, downcomer tubes leading from said lower header to said steam evaporating tubes and upcomer tubes leading from said evaporating tubes to said upper header, the connections of certain of said upcomer tubes being made into the extended portions of said header, and the remaining upcomer tubes extending upwardly within the upper header and terminating well above the bottom thereof.

11. The combination with a boiler having a plurality of rows of boiler tubes inclined somewhat from the horizontal and upper and lower box headers into which the tubes are connected, said upper box header being extended in width beyond the width necessary to accommodate said boiler tubes, of a combustion chamber associated with the boiler, 50 rows of steam evaporating tubes defining walls of the chamber, downcomer tubes leading from said lower header to said walls, upcomer tubes leading from certain of said walls to said upper header, the connections 55 being made into the extended portions of said header and at points above the level of the lower rows of boiler tubes, and upcomer tubes leading from the remaining walls to said upper header, said last mentioned upcomer tubes extending upwardly within the 60
